UNITED STATES PATENT OFFICE.

ALLISON N. CLARK, OF PLAINVILLE, CONNECTICUT.

DESIGN FOR A MATCH-BOX.

SPECIFICATION forming part of Design No. 26,252, dated November 10, 1896.

Application filed September 24, 1896. Serial No. 606,893. Term of patent 14 years.

To all whom it may concern:

Be it known that I, ALLISON N. CLARK, a citizen of the United States, residing at Plainville, in the county of Hartford and State of Connecticut, have invented and produced a new and original Design for Match-Boxes, of which the following is a specification, reference being had to the accompanying drawing, which is a perspective view of said box.

10 The leading features of my design consist in brief of a substantially rectangular figure whose ends and sides are provided with inwardly-projecting ribs at the top, said ribs forming the outline of a rectangular field

15 that is broken by a narrow bar extending lengthwise of said field. Said bar is located at one side of the longitudinal center of the said field.

The width and height of the described box are about two-thirds the length of said box. 20

The letter *a* indicates the end portions, *b* the side portions, and *c* the ribbed top portions, of my said design.

The bar which I have described as located in the upper field of the design is indicated 25 by the reference-letter *d*.

What I claim is—

The design for a match-box substantially as herein shown and described.

ALLISON N. CLARK.
